G. M. RAY

DIVIDED LAST

Filed Nov. 12, 1926

Fig. 1.

UNITED STATES PATENT OFFICE.

GEORGE M. RAY, OF NEWTON CENTER, MASSACHUSETTS.

DIVIDED LAST.

Application filed November 12, 1926. Serial No 148,057.

This invention relates to divided lasts, used in the manufacture of shoes for the purpose of reducing the strain on the upper when the last is removed from the shoe. The type of divided last which is at present most generally used has its sections connected by a hinge at its middle portion and at a distance from its bottom, and, with this type of last, as the sections are swung relatively from normal, the distance from the portion of the back end which projects to the greatest extent to the toe end, or to the front portion of the instep, is, at first, somewhat increased before it is shortened by the swinging movement, so that an additional strain is placed on the upper. In lasting low cut shoes, such as pumps or slippers, it is desirable that the uppers be drawn as tightly as possible about the front or instep portion, i. e. between this portion and the back so that when the shoe has been lasted as tightly as possible, on a hinged last of the type referred to, it is likely to be damaged by the additional stretching which is placed on the upper when it is removed from the last.

Another vital objection to the ordinary hinged last is that the heel section must be supported on the jack on which the last is placed while various operations are being performed, which must be performed on the shoe while on the last. In consequence, considerable strain is, at times, placed on the hinge connecting the sections, when pressure is applied to the bottom of the forepart, frequently causing damage thereto. Various other forms of divided lasts have been produced in an attempt to avoid the difficulty first referred to, but, so far as I am aware, in all instances when constructions have been produced which are designed to prevent an initial strain on the upper, when unlusting they have been open to other, and more vital objections, such as durability and failure to resist effectively the pressure which must be applied to the bottom thereof, during the operations which precede the removal of the shoe from the last.

The objects of my invention are to provide a form of divided last which will enable the shoe to be readily removed therefrom without in any degree increasing the strain on the upper at any time, and which will be as durable and as capable of resisting the strain, to which it must be subjected during the manufacturing operations, as if it were a solid or

one piece last. Also to provide a form of divided last which may be manufactured at a smaller expense than the type of divided last in general use.

I accomplish these objects by providing a form of last in which the heel portion is separated from the forepart on a plane which extends obliquely from the last bottom adjacent the front end of the heel seat to points adjacent the top of the last at its rear end, 60 and entirely in the rear of the jack post receiving aperture, which may be located in its usual position, and by providing means whereby said sections may be slidably connected, and moved into solid abutment, so 65 that the heel section will seat firmly on the forepart section, which will be firmly supported on the jack, when the sections are in normal relation, together with means for automatically locking said sections against 70 return movement when they are moved into said relation.

For a more complete disclosure of my invention, reference is made to the following 80 specification, in connection with the accompanying drawing, in which:

Fig. 1 is a side elevation of a last embodying my invention.

Fig. 2 is a middle longitudinal section of the heel portion thereof on a somewhat larger 85 scale.

Figs. 3 and 4 are, respectively, end views of the forepart and heel part sections thereof.

Fig. 5 is a sectional view at line 5—5 of Fig. 2. 90

Figs. 6 and 7 are detail sectional views showing the locking devices in unlocked position and

Fig. 8 is a side elevation showing a somewhat modified form of the invention. 95

As shown in the drawing a last of common form is divided, into a forepart section *a* and a heel part section *b*, by a flat plane of separation which extends obliquely, entirely in the rear of the jack post receiving recess, from a transverse line at the last bottom, which is preferably located at, or adjacent, the rear end of the shank portion of the last, to points near the top of the last and near its rear end, forming oppositely disposed corresponding faces *a*¹ and *b*¹. From this point the plane of separation is preferably extended in approximate parallelism with the bottom of the heel portion of the last, thereby forming corresponding opposite faces *a*² and *b*², so that the 100 105 110

forepart section has a longitudinal extending projecting portion a^3 , which extends to the rear end of the last.

- As the sections are separated by a sawing 5 operation, the material removed between the sections is replaced, the particular means shown for replacing this material between the rear end portion a^3 and the top of section b being a thin plate a^{30} which is secured to the 10 surface a^2 of said end portion, and may, for all purposes be considered as an integral part thereof. Lasts, as ordinarily constructed, extend above the level of the edge of the upper at the heel, when a pump or slipper 15 of common type is made thereon, and, in the present instance, the horizontal plane of separation, forming the faces a^2, b^2 is located at or above this level, as indicated by the dotted line in Fig. 1.
- 20 Means for slidably connecting the sections are provided, which comprise a flat metal plate c , secured by screws, or other suitable means, to the face a^1 of the forepart section, said plate having a slot c^1 formed in its 25 middle portion, which extends from its edge next the last bottom to a point at some distance from the face a^2 , the sides of said slot being arranged to extend convergently from the end of the plate at the last bottom and being under-cut to form, with the last, a dove 30 tail groove, as shown in Figs. 3 and 5. The corresponding face b^1 of the heel section has a metal plate d secured thereto, to form a tongue having under-cut sides, which extend 35 convergently from the last bottom, as shown in Fig. 4, and corresponds to and is adapted and arranged to fit within the slot, or groove c^1 , so that, when the narrower end of the plate d is inserted in the larger end of the 40 groove c^1 and the last sections are slid on each other, in the direction of the groove, the tongue formed by plate d will first slide in, and then will become wedged in the groove, the side edges of the tongue being seated 45 against the side edges of the groove c^1 and the smaller end of the tongue being moved into abutment with the inner end of the groove. The face b^2 will also be engaged with the face a^2 , at the same time, in which 50 position the sections a and b will be held in normal relation, so that, if the last is placed in inverted position on a jack, so that its post x will be within the thimble e of the last, the section b will have a firm bearing 55 on the section a at all possible points of contact, the portion of face b^1 , other than that to which plate d is attached, being held, throughout its entire area, in firm contact 60 with the surface of the plate c and the entire surface of the plate d being held likewise in contact with the surface a^1 , in addition to the surfaces above referred to, which are also held in contact.

Consequently, when pressure is to be applied to the bottom of the last at any point,

this pressure will be as effectively and firmly resisted as if the last were solid throughout, for the portion of the last which the jack post engages is solid with the forepart section and the latter firmly supports the heel section.

The heel section b is provided with a metal bottom plate f which projects over the end of the plate d and meets the adjacent end of a metal bottom plate g on the forepart section a . It is, however, immaterial to the invention whether a bottom plate is employed, or not.

For the purpose of automatically locking said sections a and b together when they are 80 slid relatively into their normal relation, two independent locking means are preferably provided, although either of said means only may be employed. One of said means comprises a spring actuated pin h , having a 85 rounded outer end, said pin being slidably mounted in a metal bushing i fixed within a recess b^4 in section b , said pin extending perpendicularly from the face b^2 at the meeting line of the faces b^1, b^2 . A coiled spring k is arranged within said recess between the bottom thereof and the inner end of pin h , which is provided with a flange h^1 at its 90 inner end which is adapted to engage the inner end of the bushing i and limit the outward movement of pin h by the spring at a point at which the pin will project a substantial distance beyond the surface b^2 . The rear end portion a^3 of the forepart section is provided with an aperture, which extends entirely therethrough and is lined with a metal bushing m , the arrangement being such that the outer end portion of pin h will be forced into, and will fit closely within the bushing m , when the last sections 95 are in normal position, thereby positively engaging the forepart section and preventing opposite movement of the heel section.

A dog n is mounted to swing on a pivot o within a slot a^4 formed in the section a and opening to the face a^1 thereof in perpendicular relation, said dog being arranged close to the face a^1 and extending approximately parallel thereto. A tooth n^1 is formed on the end portion of the dog next the last bottom, at one end thereof, the side of the tooth next the last bottom being inclined and the other side thereof extending perpendicular to the side of the dog. The plate d has an aperture d^1 formed therein in position to receive said tooth, and the arrangement is such that, when the last sections are in normal position, the tooth will enter said aperture d^1 and the perpendicular side thereof will be engaged with the adjacent side of the aperture. A coil spring p is arranged within a recess a^5 in section a in position to engage the end of dog n , directly opposite the tooth n^1 , so that the spring will act to press this end of the dog outwardly. The 100 105 110 115 120 125 130

opposite end of the dog extends across and into the inner end of the jack thimble hole a^6 , which opens into the slot a^4 .

Assuming that the last sections are separated, and it is desired to restore them to normal, the section b will be placed in such a position that the smaller end of plate d will be disposed within the groove c^1 , and the sections will be pressed together, so that their adjacent flat surfaces will be in contact. This action will cause the rounded end of the pin i to be pressed against the surface of plate c , forcing it inward, and at the same time pressure of the plate d on the tooth of dog n will cause the dog to be swung back within its slot a^4 . The section b will then be slid down on the section a until it has been moved into normal position, so that the pin i will be forced by its spring into the bushing m . At the same time, the dog n will be swung outward by its spring p , so that its tooth will enter the aperture d^1 and its square side will engage the inner side of the aperture. As a result the sections will be firmly locked together at two different points, each locking device reinforcing the other, and if one should fail to act the other would be likely to do so.

It is to be noted that the pin h does not, when the sections are in normal relation, project above the top surface of the section a . Also the dog n is so arranged, that, when the last is placed on a jack, having its post x of the usual length, the end of the post will not engage the end of the dog which extends into the inner end of the thimble hole, as shown in Fig. 2, so that, during any of the ordinary operations on the shoe while on the last there is no liability that either locking means will be released, so as to permit disconnection of the last sections. When, however, the shoe is to be removed from the last, the last will be placed on a special jack having a post y which is slightly longer than the other jack posts, so that its end will engage the end of the dog n , and swing it so as to disengage its tooth from the heel section, as shown in Fig. 6. A rod z is also mounted on the special jack which is arranged to enter the bushing m and be pressed against the end of the pin h as the last is pressed down on the jack post, forcing it inward until it becomes disengaged from the section a , as shown in Fig. 7, thereby releasing the section b from section a and permitting it to slide up thereon. Usually the tension of the upper, when lasted as tightly as it should be, will be sufficient to move the section b to such an extent that neither locking device may become reengaged, so that it is then merely necessary for the operator to grasp the heel of the shoe and pull it from the forepart section, removing the heel section with the shoe, from which the heel section will be later removed, and restored to its normal position on the forepart section.

Under ordinary conditions, as previously explained, the top edge of the upper at the back of the shoe does not extend onto the end portion a^3 , but terminates at the level of the plane of separation $a^2 b^2$, as indicated by the dotted line in Fig. 1, so that the back end of the end portion a^3 does not engage the upper or interfere with its ready removal and the entire portion of the back end of the last which engages the upper moves towards the front end thereof when released.

If, however, a high shoe were to be made on the last, the construction may be somewhat modified, as indicated in Fig. 8. That is, the oblique plane of separation may be extended directly to the top of the last, in the rear of the jack post receiving recess, and forming sections a^0 , b^0 , so that the entire rear end of the last will move upward and towards the forepart when the sections are unlocked. In this instance the locking pin h and associated parts, would be omitted and the plate c^0 , corresponding to plate c , would be extended throughout the plane of separation. In some respects, this construction is not as desirable as the other, as a horizontal support is not provided by the forepart section for the heel section, but in some other respects it may be more desirable, particularly as it is less expensive to construct.

With the above described construction it is possible to make the top portion of the last as thin as may be desired, so that the sides of the foot opening will be drawn closely to the foot of the wearer, and to have the back end rounded out as much as may be desired to receive the heel of the wearer and yet have the top portion of the upper at the back hug closely to the foot, so that the shoe will not slip at the heel when worn. Also, the construction permits the shoe to be lasted, or the upper drawn lengthwise as tightly as may be desired, without incurring danger of overstraining the upper when the last is pulled out, these results being all incidental to the fact that the shortening movement of the last sections is such that no additional strain is at any time placed on the upper.

As the plane of separation of the sections is in the rear of the jack post recess, so that the forepart section is supported directly on the jack post, an important source of damage to divided lasts is eliminated, hinged lasts of the ordinary type being frequently broken or damaged by pressure on the shank and forepart of the bottom while supported on a jack, the construction herein shown being considered as rigid and durable as if the last were of one piece.

The above described construction is also advantageous from a manufacturing standpoint, for the reason that the work which must be performed on the last in preparation for the application of the connecting means

for the sections is substantially simplified, as compared with previous constructions for the same purpose, for the entire last must first be made in one solid piece of wood in the usual manner, and, when it is separated into sections, this is done by a mere saw cut, the width of which is exactly equal to the thickness of the plate *c*, so that, when the latter is placed in position, the wood which has been removed by the separating operation is entirely replaced, the outline of the plate *c* corresponding to the outline of the faces left by the saw cut. When the cut is not extended thru to the top of the last, the wood removed by the cut which is made parallel to the heel seat will be replaced by the flat piece *a*³⁰, as already explained. As the tongue plate *d* is of practically the same thickness as the slotted plate *c*, and is entirely received by the slot therein, no further cutting or grooving of the last is necessary in preparation for the metal parts, aside from the formation of the bore for the locking pin, when this form of locking means is alone used.

25. I claim:

1. A last comprising separable heel and forepart sections having oppositely disposed transverse faces of separation extending obliquely from the last bottom adjacent the rear end of the shank portion rearwardly towards the top and then horizontally, in approximate parallelism with the heel portion of the bottom, to the back end of the last, and means movable to lock said sections against separation when in normal relation.

2. A last comprising separable heel and forepart sections having oppositely disposed transverse faces of separation extending obliquely from the last bottom adjacent the rear end of the shank portion rearwardly towards the top and then horizontally, in approximate parallelism with the heel portion of the bottom, to the back end of the last, said sections having a tongue and a corresponding groove arranged for interlocking engagement as the heel section is moved on the forepart section, with said oblique faces in contact, from the bottom towards the top thereof and means movable to lock said sections against opposite movement when said horizontal faces are engaged.

3. A last comprising separable heel and forepart sections having oppositely disposed transverse faces of separation extending obliquely from the last bottom adjacent the rear end of the shank portion towards the top and then horizontally, in approximate parallelism with the heel portion of the bottom, to the back end of the last, one of said sections having an undercut groove and the other a corresponding tongue arranged for interlocking engagement as the heel section is slid on the forepart section, with said oblique faces in contact, from the bottom towards the top thereof, and means movable

to lock said sections against opposite movement when said horizontal faces are brought into contact.

4. A last comprising separable heel and forepart sections having oppositely disposed transverse faces of separation extending obliquely from the last bottom adjacent the rear end of the shank portion towards the top and then horizontally, in approximate parallelism with the heel portion of the bottom, to the back end of the last, one of said sections having an undercut groove and the other a corresponding tongue arranged for interlocking engagement as the heel section is slid on the forepart section, with said oblique faces in contact, from the bottom towards the top thereof, a locking pin reciprocally mounted in said heel section in perpendicular relation to the horizontal face thereof and spring actuated to engage the forepart section when said horizontal faces are moved into contact and means permitting engagement with said pin from the top of the forepart section to disengage the pin therefrom.

5. A last comprising a forepart section having a jack-post-receiving recess opening to its top, a heel section divided therefrom by a transverse plane of separation which extends obliquely from the last bottom at points adjacent the rear end of the shank portion, towards the rear end of the last, and in the rear of said recess, means including a tongue and groove connection between said sections to permit said heel section to slide on the forepart section from the top towards the bottom thereof and into normal relation therewith, and a locking device mounted in the forepart section and normally actuated to engage the heel section as it is moved into normal relation with the forepart section, to lock it against opposite movement, said locking device having means at the inner end of said recess arranged to be actuated by the jack post when inserted in said recess to disengage the same from said heel section.

6. A wooden last transversely divided to form heel and forepart sections having transverse faces of separation extending obliquely from the last bottom, a metal plate of a thickness corresponding to the material removed in separating the last secured to the face of one of said sections and having its edges flush with the adjacent side surfaces of the sections, and continuous therewith, said plate having an undercut slot therein extending in a direction from top to bottom of the last and the face of the other section having an undercut metal tongue thereon corresponding to said slot and adapted to permit the face portion of the section about the tongue to be directly engaged with the surface of said plate and the heel section to be moved slidably on the forepart section into normal relation therewith, and locking means arranged to hold said sections against separation when in

said relation and operable from the top of the last to permit separation thereof.

7. A wooden last transversely divided to form heel and forepart sections having transverse faces of separation extending obliquely from the last bottom, a metal plate of uniform thickness secured to the face of one of said sections and having its edges flush with the adjacent surfaces of the sections when held in normal relation, said plate having an under cut slot extending from the bottom end thereof towards the top and the face of the other section having a corresponding metal tongue thereon and arranged to be passed into said slot, to permit the sections to be slidably engaged, and means for locking said sections against relative sliding movement when in normal relation.

8. A wooden last transversely divided to form heel and forepart sections having parallel faces of separation extending obliquely from the last bottom towards the top and

back end, a metal plate of uniform thickness secured to the face of one of said sections, having its edges flush with the sides of the section, and having an under cut slot open at its bottom end and extending towards the top of the section, the other section having on its face a tongue corresponding to said slot and adapted to be received thereby as the heel section is slidably moved on the forepart section from the bottom towards the top thereof, said sections having abutting faces arranged to be engaged when the sections are in normal relation, locking means in one of said sections arranged for engagement with the other section when said faces are in abutment, to prevent opposite movement of the heel section, and means permitting actuation of said locking means from the top of the last to permit said opposite movement.

In testimony whereof, I have signed my name to this specification.

GEORGE M. RAY.
